[57] CLAIM

The ornamental design for a weaponry bracket assembly, as shown and described.

DESCRIPTION

FIG. 1 is a perspective view of a weaponry bracket assembly showing my new design;

FIG. 2 is a top view thereof;

FIG. 3 is a front elevational view thereof;

FIG. 4 is a bottom view thereof, as seen in FIG. 5;

FIG. 5 is a rear elevational view thereof;

FIG. 6 is a left side elevational view thereof; and,

FIG. 7 is a right side elevational view thereof.

The broken line showing of the interior bed of a pickup truck and a rifle in FIG. 1, and of a vertical mounting surface in FIGS. 4, 6 and 7 is for illustrative purposes only and forms no part of the claimed design.

FIG. 1

FIG. 2

FIG. 3

FIG. 4

FIG. 5

FIG. 7

FIG. 6
